SAFETY RAZOR

Morehead Patterson, New York, N. Y., assignor
to Durham Duplex Razor Company, a corpora-
tion of New York

Application December 31, 1935, Serial No. 56,882

4 Claims. (Cl. 30—62)

This invention relates to an improvement in safety razors having for its main object the production of a simple, efficient and inexpensive device of this character in which blades of different 5 make whether of the flexible or non-flexible type, may be used. With this and other objects not specifically mentioned in view, the invention consists in certain constructions, combinations and elements thereof which will be hereinafter fully 10 described and then specifically set forth in the claims hereunto appended.

In the accompanying drawing, in which like characters of reference indicate the same or like parts, Fig. 1 is a side view of a device constructed 15 in accordance with the invention; Fig. 2 is a front view of said device, as seen from the line 2—2 in Fig. 1; Fig. 3 is a cross sectional view taken on the line 3—3 in Fig. 2; Fig. 4 is a face view of the clamp shown in Figs. 1 and 3; Fig. 20 5 is a face view of said clamp assembled with an Enders blade; and Fig. 6 is a face view of said clamp assembled with a Christy blade.

In carrying the invention into effect, there is provided a razor frame having a blade seat and 25 provided with clamp holding means arranged angularly with respect to said seat and with means to prevent rearward movement of a blade and said clamp, and a clamp having spring engagement with said clamp holding means to hold 30 a blade between said seat and said clamp.

In the best constructions contemplated, the razor frame has clamp holding means or surfaces at both of its ends, and the clamp has spring lugs at both of its ends to engage said 35 surfaces; the clamp lugs slidably engage the clamp holding means or surfaces of the razor frame; and the clamp lugs are integral with its body portion, the clamp as a whole being normally flat when detached from the frame.

40 Referring to the drawing, which illustrates but one embodiment of the invention, the razor frame 7 has a blade seat 8 against which a blade 9 rests. The blade may be of the flexible Enders type shown at 9E in Fig. 5, or of the non-flexible 45 Christy type shown at 9C in Fig. 6, or of any other type suitable for use in the frame 7.

The frame 7 is also provided at each of its ends with clamp holding surfaces 10 arranged angularly with respect to the blade seat 8. These 50 surfaces are engaged by spring lugs 11 formed on the ends of a clamp 12, the clamp being normally flat when detached from the frame. To avoid interference with the cutting edge of the blade used, the clamp 12 is narrower than said blade.

55 The frame 7 is also provided with ledges 13, 13

to engage the rear edge of the blade used and the clamp 12 to prevent rearward movement thereof when the device is in use.

To assemble the parts of the razor, a blade 9, 9E, or 9C, is placed on the blade seat 8, and the clamp 12 is pushed down behind the blade until its rear edge snaps into engagement with the ledges 13, 13. As the clamp moves down, its spring lugs 11 come into engagement with the clamp holding surfaces 10 and are flexed thereby to cause the clamp to hold the blade firmly between the blade seat and the clamp. To take the parts apart, it is only necessary to withdraw the clamp from the frame, thus freeing the blade.

Changes and variations within the scope of 15 the claims may be made in the structure by means of which the invention is carried into effect. The invention, therefore, is not to be restricted to the precise details of the structure 20 shown and described.

What is claimed is:

1. The combination with a razor frame fabricated throughout of substantially rigid material, and having a blade seat provided at its ends with rigid clamp-holding surfaces; of a blade; 25 and a normally flat clamping member having at its ends integral spring lugs and engaging said surfaces slidably to hold the blade between said seat and said clamp, said spring lugs operating in conjunction with said holding surfaces to compensate for variations between blades of various shapes, and said blade seat having its material relieved at its medial portion to permit ready manipulation of the blade at its rearward edge, for insertion, adjustment and removal. 30

2. In a safety razor, the combination with a blade seat, of a blade positioned on said seat, a handle secured to said seat, and a flat clamp unsecured to said handle and having a resilient portion adapted to be flexed by engagement with 40 said seat to hold the blade between the clamp and seat, without flexing the blade said resilient portion being normally disposed in the plane of the body portion of the clamp at the end thereof.

3. In a safety razor, the combination with a 45 blade seat provided with a slideway adapted to engage and flex a clamp, of a blade positioned on said seat, and a flat clamp having a resilient portion adapted to be flexed by engagement with said way to hold the blade between the seat and 50 clamp, the slideway being disposed obliquely of the blade seat, and said resilient portion being normally disposed in the plane of the body portion of the clamp.

4. In a safety razor, the combination with a 55

holder having a blade seat on to which may be inserted edgewise a rigid blade having a cutting edge on its forward longitudinal edge, a clamp adapted to be inserted edgewise over the previously inserted blade and provided with flexible tongues extending from its ends toward the cutting edge of the blade, and means on said holder for flexing said tongues and thereby causing said

blade to be held between said clamp and blade seat, said holder also being provided with ledges arranged to engage the rearward longitudinal edge of said clamp to prevent transverse displacement of the clamp and blade on the blade seat, said tongues being disposed in the plane of the body portion of said clamp. 5

MOREHEAD PATTERSON.
